(57) **CLAIM**

The ornamental design for a stackable model component as shown and described.

DESCRIPTION

FIG. 1 is a top, front perspective view of a stackable model component in an unfolded configuration in accordance with our new design;

FIG. 2 is a top, rear perspective view of the stackable model component of FIG. 1;

FIG. 3 is a front view of the stackable model component of FIG. 1;

FIG. 4 is a rear view of the stackable model component of FIG. 1;

FIG. 5 is a side view of the stackable model component of FIG. 1;

FIG. 6 is a side view of the stackable model component of FIG. 1;

FIG. 7 is a top view of the stackable model component of FIG. 1;

FIG. 8 is a bottom view of the stackable model component of FIG. 1;

FIG. 9 is a top, front perspective view of a stackable model component in a partially folded configuration in accordance with our new design;

FIG. 10 is a top, rear perspective view of the stackable model component of FIG. 2;

FIG. 11 is a front view of the stackable model component of FIG. 9;

FIG. 12 is a rear view of the stackable model component of FIG. 9;

FIG. 13 is a side view of the stackable model component of FIG. 9;

FIG. 14 is a side view of the stackable model component of FIG. 9;

FIG. 15 is a top view of the stackable model component of FIG. 9; and,

(Continued)

FIG. 16 is a bottom view of the stackable model component of FIG. 9.

The portions shown in broken lines illustrate structure and/or features that form no part of the claimed invention.
